US0D1001170S

(12) **United States Design Patent** (10) **Patent No.:** **US D1,001,170 S**
(45) **Date of Patent:** **** Oct. 10, 2023**

(54) **VORTEX TUBE**

(71) Applicant: **Nex Flow Air Products Corp.**,
Richmond Hill (CA)

(72) Inventor: **Amanjot Singh**, Brampton (CA)

(73) Assignee: **Nex Flow Air Products Corp.**,
Richmond Hill (CA)

(**) Term: **15 Years**

(21) Appl. No.: **29/843,927**

(22) Filed: **Jun. 24, 2022**
